UNITED STATES PATENT OFFICE

THOMAS B. LAMB, OF NEW YORK, N. Y., ASSIGNOR TO AGFA ANSCO CORPORATION, OF BINGHAMTON, NEW YORK, A CORPORATION OF NEW YORK

DESIGN FOR A CAMERA

Application filed January 9, 1932. Serial No. 42,423. Term of patent 14 years.

To all whom it may concern:

Be it known that I, THOMAS B. LAMB, a citizen of the United States, residing at 280 Madison Ave., New York city, in the county of New York and State of New York, have invented a new, original, and ornamental Design for Camera, of which the following is a specification, reference being had to the accompanying drawings, forming part thereof.

Figure 1 is a side view of a camera in open position showing my new design.

Figure 2 is a side view of a camera in closed position.

Figure 3 is a front view of the same in a closed position and on a reduced scale.

I claim:

The ornamental design for a camera, as shown.

THOMAS B. LAMB.
